UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A BRUSH-BACK.

SPECIFICATION forming part of Design No. 24,330, dated May 28, 1895.

Application filed May 4, 1895. Serial No. 548,172. Term of patent 3½ years.

To all whom it may concern:

Be it known that I, CHARLES OSBORNE, of New York city, in the county and State of New York, have invented a new and original 5 Design for Brush-Backs and Similar Articles, of which the following is a full, clear, and exact description.

Reference is to be had to the accompanying drawings, in which Figure 1 represents a back 10 view of a brush having a back embodying my new design, and Fig. 2 represents a front view of the handle-part of the brush-back.

The leading feature of my design consists 15 in the ornamentation of the back, consisting of forget-me-nots and conventionalized floriate scrolls framing the substantially plain sur-

face, with festoons beneath a shell-like figure at the top of such surface.

Minor features are the shield at the back 20 of the handle portion framed by conventionalized floriate scrolls or stems, with forget-me-nots above and below the shield, and the ornamentation at the front of the handle, consisting of conventionalized scrolls, as shown, framing a sprig of forget-me-nots. 25

I claim—

The design for a brush back or similar article, herein shown and described.

CHARLES OSBORNE.
